UNITED STATES PATENT OFFICE.

CHARLES RIPPIN, OF ST. LOUIS, MISSOURI.

GRAIN-SCOURER.

SPECIFICATION forming part of Letters Patent No. 451,580, dated May 5, 1891.

Application filed February 25, 1891. Serial No. 382,693. (No model.)

To all whom it may concern:

Be it known that I, CHARLES RIPPIN, of the city of St. Louis, and State of Missouri, have invented certain new and useful Improvements in Grain-Scourers, of which the following is a full, clear, and exact description, reference being had to the accompanying drawings, forming a part hereof.

My invention relates to improvements in grain-scourers; and it consists in the novel arrangement and combination of parts, as will be more fully hereinafter described and designated in the claims.

In the drawings, Figure 1 is a vertical section of my machine, taken on line $z z$ of Fig. 3. Fig. 2 is a horizontal cross-section taken on the line $x x$ of Fig. 1. Fig. 3 is a vertical cross-section taken on the line $y y$ of Fig. 2; and Fig. 4 is a cross-section of one of the 20 spiral wings or vanes, showing its corrugated surface and also the small bolts or lugs which pass through the same.

Referring to the drawings, 1 indicates the case or boxing, the same being suitably 25 mounted upon any appropriate supports.

2 and 3 indicate parallel shafts, the former of which is mounted in suitable bearings 4 in the case or boxing 1. To the shafts 2 and 3, at one end, are secured in any mechanical 30 manner gear-wheels 5, the teeth of which mesh into each other, so that one of the said shafts will be driven from the other, and the two shafts will revolve in opposite directions, and to one of the ends of one of the said shafts

35 an ordinary belt-pulley 3^a is adapted to be secured to receive a driving-belt from any convenient power. Encircling said shafts are spiral wings or vanes 6. One of the said spiral wings or vanes is a right one and the 40 other is a left spiral wing or vane. The shafts 2 and 3 are placed at such a convenient distance apart that the paths of the spiral wings or vanes 6 will overlap each other, as indicated and shown in Figs. 2 and 3. Shaft 3 is 45 adjustable relative to shaft 2, and according to the peculiar nature and construction of the spiral wings 6 when shaft 3 is adjusted approximately close to shaft 2, the wings 6 will be brought close together. By this means 50 it is evident that the distance between the faces of the spiral wings or vanes 6 may be regulated, as desired, corresponding, of course,

to the size of the grain that is desired to be rubbed by them. The adjustment of shaft 3 is effected by thumb-screws 7, which thumb-screws are adapted to move the adjustable bearings 8, in which said shaft 3 is mounted. The bearings 8 are movable along in the case 1, as desired. The spiral wings or vanes 6 are provided with a series of sections 9 of 60 parallel corrugations 10, as can be seen by inspecting Fig. 3. The sections 9 are arranged segmentally, and each of said sections is provided with parallel corrugations, as before stated, and the parallel corrugations of 65 each section being formed at angles with the parallel corrugations of the adjacent sections. The object of these corrugations is to elevate the grain and spread the same over the entire surface of the vanes 6 as the same revolve. 70

11 indicates lugs or bolts, which are suitably secured in spiral wings or vanes 6. Said lugs are secured in said spiral wings by means of small nuts 11^a, which are adapted to be screwed on the ends of the same. Said lugs 75 are so arranged in the vanes that the lugs secured in one spiral wing or vane will pass without coming in contact with the lugs secured in the other wing or vane, as can be readily perceived by inspecting Fig. 2. The 80 object of these lugs is to elevate and stir up the grain, and also to increase the friction-surface that is brought to bear on the grain. Said lugs should be of such a size as not to interfere with the adjusting of the spiral 85 wings or vanes 6.

12 indicates a perforated shaker or shifting device, which is located directly beneath the extremities of the spiral wings 6, but not in such a position as to interfere with the revolving or rotating of the same. Said shaker is preferably constructed by taking a piece of sheet metal and punching or stamping it full of perforations of suitable size as to admit the passage of the dust and small particles of foreign substances that have been removed from the grain. 90

13 indicates springs, one end of which is secured to shaker 12 and the other to the case or boxing or to any other part of the device 100 as mechanical ingenuity may suggest. Said springs also have the function of supporting said shaker 12 and giving the same a vibratory motion by the agency of a disk 14, rig-

idly secured at an angle to shaft 2, which disk is adapted to move between collars 16, which collars are rigidly secured to a horizontal moving shaft 17. By this brief explanation the operation is readily perceived. The disk 14, revolving as shaft 2 does and being set at an angle on the same, will throw shaft 17 in a horizontal direction, which shaft strikes against the shaker 12, and with the agency 10 of springs 13 will give the same a vibratory and shaking motion.

18 indicates an opening through which the grain passes from the shaker into a spout 19, which leads to any suitable receptacle for the 15 cleansed grain.

20 indicates a dust-conveyer, which is mounted in suitable bearings in the lower part of box or casing 1, the function of which is to convey the dust and small particles of foreign 20 substances that have been removed from the grain out of the box or casing 1 into any desired receptacle through a chute or spout 21. Said conveyer is revolved by a belt 22, which passes over suitable belt-pulleys secured to 25 shaft 2 and the shaft of the conveyer, as can be readily perceived in Fig. 1.

23 indicates a draft flue or conduit, one end of which communicates with spout 19 or the spout from which the grain passes after being 30 cleansed, and the other end of the same communicates with a fan-box 24, in which a fan 25 is located. Said fan is mounted on a shaft 26, which shaft has its bearings in a support 27 and also in the draft-conduit 23, as can be readily perceived in Fig. 1.

28 indicates a belt-pulley which is secured to one end of shaft 26, and said fan 25 is rapidly turned by means of a belt 29, which passes over belt-pulley 28 and over a belt-pulley 30, secured to shaft 2. The function of said fan, of course, is well understood; but it would not be inopportune to give a brief explanation of the same in its connection in this specific device. Of course, as the grain passes 40 from spout 19 it is bound to contain a considerable amount of dust and chaff, and a draft caused by the fan will suck or draw the same from the grain and convey it up the conduit 23. If, perchance, the influence of the fan 45 should attract any of the grain in its passage up the conduit 23 and across the horizontal portion of the same, the grain, being of greater specific gravity than the dust, will fall and may be accumulated in a hopper or receptacle 31, which is in communication with the draft-conduit 23. Said receptacle has secured to it a valve 32, which is held or adapted to be held in a closed position by the suction influence of the fan; but when sufficient 50 grain has accumulated in receptacle 31 of course such accumulation will open the valve 32 and permit the removal of the grain that has been accumulated in said receptacle by its own weight.

65 33 indicates a supply-spout through which the grain may be inserted and brought in contact with the abrasive influence of the spiral

wings or vanes 6, and is there operated upon by said wings until the friction has removed the rust and foreign accumulations, such as 70 incrustations formed upon the grain. When the grain has been sufficiently operated upon so as to cleanse it, it then comes in contact with the shaker 12, and the accumulation that has been removed from the grain is 75 sifted out of the same and falls down in the bottom of the box or casing 1, and is there removed, as hereinbefore stated. The spiral wings or vanes 6, while possessing the function of cleansing the grain, also convey the same to 80 opening 18 in the shaker. Before the grain is introduced, however, to the abrasive action of the spiral wings or vanes, it should first be passed through a receiving shaker or sifter and have all the large foreign particles re- 85 moved from it, such as stones, &c.

Having fully described my invention, what I claim is—

1. A grain-scourer consisting of a case or boxing 1, two parallel shafts, one of which is 90 adjustable relative to the other and both mounted in suitable bearings in said case or boxing, and each of said shafts provided with a right and left spiral wing or vane, respectively, and each wing or vane provided with 95 segmental sections of parallel corrugations, gear-wheels adapted to mesh with each other secured to said shafts, and a suitable belt-pulley adapted to be secured to one end of one of the said shafts to receive a driving-belt, whereby 100 said shafts, and consequently said spiral wings or vanes, may be rotated, substantially as set forth.

2. A grain-scourer consisting of a case or boxing 1, two parallel shafts, one of which is 105 adjustable relative to the other and both mounted in suitable bearings in said case or boxing, and each of said shafts provided with a right and left spiral wing or vane provided with segmental sections 9 of parallel corrugations 10, screw-threaded lugs 11, adapted to be secured in said wings or vanes, gear-wheels adapted to mesh with each other secured to said shafts, and a suitable belt-pulley adapted to be secured to one end of one 110 of the said shafts to receive a driving-belt, whereby 115 said shafts, and consequently said spiral wings or vanes, may be rotated, substantially as set forth.

3. A grain-scourer consisting of a case or 120 boxing 1, two parallel shafts, one of which is adjustable relative to the other and both mounted in suitable bearings in said case or boxing, and each of said shafts provided with a right and left spiral wing or vane, the same 125 being provided with segmental sections 9 of parallel corrugations 10, screw-threaded lugs 11, adapted to be secured in said wings or vanes, gear-wheels 5, adapted to mesh with each other, secured to said shafts, and a suitable belt-pulley secured or adapted to be secured to one end of one of the said shafts to receive a driving-belt, whereby 130 said shafts, and consequently said spiral wings or vanes,

may be rotated, a perforated shaker 12, located below said wings and supported by springs 13, a horizontally-movable shaft 17, provided with shoulders 16, situated so as to 5 strike against said shaker, a disk 14 rigidly, secured to shaft 2, for giving said shaft 17, and consequently shaker 12 with the agency of spring 13, a vibratory motion, an opening 18 in said shaker for the passage of the grain, a spout 19 for conducting the same to any desired receptacle, and a dust-conveyer 20, located in 10 said bearing in the bottom of box or casing 1, substantially as set forth.

4. A grain-scourer consisting of a case or 15 boxing 1, two parallel shafts, one of which is adjustable relative to the other and both mounted in suitable bearings in said case or boxing, and each of said shafts provided with a right and left spiral wing or vane, the same being provided with segmental sections 9 of parallel corrugations 10, screw-threaded lugs 11, adapted to be secured in said wings or vanes, gear-wheels 5, adapted to mesh with each other, secured to said shafts, and a suitable 20 belt-pulley secured or adapted to be secured to one end of one of the said shafts to receive a driving-belt, whereby said shafts, and consequently said spiral wings or vanes, may 25

be rotated, a perforated shaker 12, located below said wings and supported by springs 13, 30 a horizontally-movable shaft 17, provided with shoulder 16, situated so as to strike against said shaker, a disk 14, rigidly secured to shaft 2, for giving said shaft 17, and consequently shaker 12 with the agency of springs 35 13, a vibratory motion, an opening 18 in said shaker for the passage of the grain, spout 19 for conducting the grain to any desired receptacle, and a dust-conveyer 20, located in suitable bearings in the bottom of box of casing 1, a draft-conduit 23, one end of which communicates with spout 19 and the other with a fan-box 24, in which is located in suitable bearings a fan 25, a receptacle 31, provided with a valve 32 in communication with 40 said conduit, for receiving the grain that is sucked up the conduit, and suitable belting for driving said conveyer, fan, &c., substantially as set forth.

In testimony whereof I affix my signature 45 in presence of two witnesses.

CHARLES RIPPIN.
